United States Patent Office

Des. 208,443
Patented Aug. 29, 1967

208,443

DISPLAY RACK

Clark B. Rollins, Jr., 1415 Elm Hill Road,
Nashville, Tenn. 37210

Filed Jan. 16, 1967, Ser. No. 5,436

Term of patent 14 years

(Cl. D80—10)

Fig. 1

FIG. 1 is a front perspective view of the display rack embodying my new design.

FIG. 2 is a side elevation thereof; and

FIG. 3 is a top plan view thereof.

I claim:

The ornamental design for a display rack, as shown.
